UNITED STATES PATENT OFFICE.

JAMES W. PIPKIN AND HILLARD S. MITCHELL, OF WILTON, ARKANSAS.

PNEUMATIC SIGNAL FOR RAILWAY-CROSSINGS.

No. 874,622.

Specification of Letters Patent.

Patented Dec. 24, 1907.

Application filed May 14, 1907. Serial No. 373,583.

To all whom it may concern:

Be it known that we, JAMES W. PIPKIN and HILLARD S. MITCHELL, citizens of the United States, residing at Wilton, in the 5 county of Little River and State of Arkansas; have invented certain new and useful Improvements in Pneumatic Signals for Railway-Crossings, of which the following is a specification.

This invention appertains to signaling means for railway crossings either where two railroads intersect, or where a highway or public road crosses a line of railway, the purpose being to notify any one at the crossing 15 of the approach of a train, thereby preventing a casualty.

The invention contemplates both visual and audible signaling means and a fluid medium, such as air, for actuating the same, a 20 pipe line extending from the signaling means to a pump or air compressor to convey compressed air to the signaling means for actuating the same when the air compressor is operated by an approaching train.

25 In the event of the invention being adapted to a roadway, signaling means are arranged at one or each side of the railroad to be simultaneously operated, thereby giving ample warning from either approach. At a 30 crossing of two railroads, signals are arranged for each approach, three of such signals being simultaneously operated to give ample and proper warning both to the engineer and to advise him of the proper workings of the system, and to any one approaching the crossing to apprise them of impending danger.

35 For a full description of the invention and the merits thereof and also to acquire a 40 knowledge of the details of construction and the means for effecting the result, reference is to be had to the following description and accompanying drawings.

45 While the invention may be adapted to different forms and conditions by changes in the structure and minor details without departing from the spirit or essential features thereof, still the preferred embodiment is shown in the accompanying drawings, in 50 which:

55 Figure 1 is a top plan view of a railway crossing equipped with safety appliances embodying the invention. Fig. 2 is a perspective view of the crossing showing the safety appliances in connection with two approaches. Fig. 3 is a top plan view of a com-

pressible strip for actuating the air compressor and adapted to rock for bleeding the system to admit of the parts returning to normal position. Fig. 4 is a longitudinal section 60 on the line 4—4 of Fig. 3. Fig. 5 is a sectional view on the line 5—5 of Fig. 4, showing the support at one end of the compressible piece to admit of the same rocking. Fig. 6 is a detail view of the secondary semaphore 65 signal and the operating means for side tracking or causing the train to leave the main track. Fig. 7 is an end view of the relief valve showing a portion of the operating rod. Fig. 8 is a detail view of the lantern or night 70 signal and the operating means for effecting turning thereof.

Corresponding and like parts are referred to in the following description and indicated in all the views of the drawings by the same 75 reference characters.

At the crossing of two tracks 1 and 2 is arranged a four-way coupling E from which pipes 3 lead to the air compressing means. For convenience the four approaches to the 80 crossing are designated by the reference letters A, B, C and D. Each approach is similarly equipped with safety and signal appliances indicated, respectively, by the reference letters F, G, and H. Air compressing 85 means J are provided for each approach and are adapted to be operated by the train or car approaching the crossing. The signal devices F and G are located some distance apart, the former being actuated by means of a train from any approach other than that upon which the train is moving towards the crossing. The signal G is brought into play when two trains or cars are approaching the 90 crossing from opposite directions, so as to give ample warning of impending danger. The safety appliance H is to effect side tracking of the train should the same pass by both signals F and G when they are set, to indicate danger.

100 The air compressor consists of a cylinder 4, a piston 5 arranged to operate in the cylinder and having a projecting stem 6, and check valves 7 and 8. The check valve 7 opens inward or towards the cylinder to admit air thereto when the piston 5 is moved upward in the cylinder 4. The check valve 8 opens outward away from the cylinder to admit air being forced into the main pipe 3 when the piston is depressed by the action of the train or car. When the check valve 8 is open, the check valve 7 is closed, and vice 105 110

versa. The piston 5 is pressed upward preferably by means of a spring 9 located within cylinder 4 so as to be housed and protected thereby. Openings 10 are formed in the upper end of the cylinder for ingress and egress of air so as not to affect the movements of the piston which would otherwise result if no vents were provided. The compressor is preferably arranged between the rails of the track and adjacent to one of the rails and between the adjacent ties, and occupies an upright position, so that the weight of the car may be utilized for depressing the piston and thereby charge the main pipe and signal and safety appliances with air under pressure sufficient to insure positive and certain operation thereof. A depressible strip, plate or bar 11 extends over the stem 6 and is of bow form, its end portions being connected by suitable means to a plate or bed. The strip 11 is resilient and is located adjacent to the rail in proximal relation to the compressor so as to receive direct pressure from the wheels of the car, locomotive or the like passing thereover. When a car is moving towards the crossing, the strip or plate 11 is depressed by the wheels passing thereover. The downward movement of the piston within the cylinder charges the main pipe 3 with air which is utilized for operating the signal and safety appliances in the manner hereinafter stated. The strip 11, in addition to its depressible movement, is mounted as indicated in Fig. 5 to receive a rocking movement, the latter motion being utilized to open a valve 12 by means of which the stem is relieved of compressed air and the parts permitted to return to normal position. To effect this result a portion of the strip for a short distance from one end is cut away as indicated at 13, forming a space between the edge of the strip and the adjacent rail into which the flange of a car wheel enters and forces said strip 11 away from the rail. The cut away portion 13 is at the end of the strip facing the corner, and said strip is adapted to be rocked or moved away from the rail by a train or car when receding from the crossing only. The strip 11 is mounted to receive a rocking movement and a lever 14 is arranged upon the inner side thereof to be operated when the strip is moved laterally, said lever being connected by means of a rod 15 to the valve 12 to effect opening of the latter when the said lever 14 is actuated. A vertical flange 16 is provided at the inner longitudinal edge of the strip to be engaged by the flange of a car wheel when approaching the corner so as to hold the strip close against the rail and prevent outward movement thereof. When the train is receding from the crossing, the flange of the wheel wedging into the space formed between the cut away portion 13 of the strip and the rail effects positive lateral movement of said strip, with the result that

the valve 12 is opened and the pipe lines and signal and safety operating means released of pressure.

The primary semaphore signal F comprises an arm 17, for use by day and a lantern 18 for use by night. The arm 17 is pivotally supported by means of a post 19. A cylinder 20 receives a piston 21 whose stem is connected by link 22 with one end of the semaphore arm 17. An audible signal 23 consisting of a whistle is connected with an end portion of the cylinder 20 to be sounded when the piston 21 is moved upward and after said piston has reached its upward movement and has cleared the connection of said signal with the cylinder. It will thus be understood that the signal 23 performs the double features of apprising one of danger and at the same time affording a vent for the cylinder at each stroke of the piston 25 therein. When the piston 21 is driven to the upper end of the cylinder, the semaphore arm 17 is lowered in the danger position, and the lantern 18 is also turned to indicate 90

The semaphore arm is depended upon to indicate danger by day, but at night the lantern 18 is utilized. Colored lenses or glasses are set in the sides of the lantern to give proper warning and in one position the lantern shows one color, or light, and in another position a different color. The relative position of the lantern is fixed by the following means: A block 24 is provided with a spiral or inclined guide way 25 with 100 which cooperates connection 26 of the lantern 18. A link 27 connects the lantern with an end of the semaphore arm 17; hence as said semaphore arm is raised or lowered the lantern is correspondingly elevated or depressed, thereby causing the connection 26 to ride in the spiral guide way 25, with the result that the lantern is given a one-fourth revolution at each upward or downward movement of the semaphore arm. 105

The secondary semaphore signal is similar to the primary semaphore signal and comprises a semaphore arm 28, cylinder 29, piston 30 arranged to operate in the cylinder 29, and connected with one arm of the semaphore, a lantern 31 connected with the opposite arm of the semaphore, and a signal 32 adapted to be operated by means of the air escaping from the cylinder 29. Neither the secondary signal nor the safety operating 115 means are brought into play by means of a train or car approaching the crossing or a given branch, that is, a train moving towards the crossing upon the approach A will not operate anyone of the signals F or G or the 120 safety appliance H on said approach, except a train shall have cleared the compressor or anyone of the other three approaches, when the secondary signal G and the safety appliance H will be brought into operation by the 130

train on the approach A. If the three approaches B, C and D are cleared, a train advancing towards the crossing on the approach A will upon reaching the compressor 5 J charge the main pipe 3 with air under pressure, and said air will pass to the four-way valve E and from thence about each of the three primary signals F, of the other three approaches B, C and D, so as to give 10 warning that a train is approaching the crossing. Should the car or train move towards the crossing upon the approach A, and observe the primary signal F set, it is an indication that someone of the other approaches is occupied, but should the train 15 neglect to heed the said signal F and pass by the same, the train in passing over the compressor will set the signal G and operate the safety appliance H and upon approaching 20 will find signal G set, and should this signal go unheeded and the train continue to approach, it will be either side-tracked or ditched, thereby clearing the main line. A 25 valve is provided for each approach and may be of any construction so long as it serves to prevent operation of the primary signal on the approach occupied by the moving train.

As shown in Fig. 6, the valve consists of a 30 box 33 with which the main pipe 3 and branch pipe 34 connect. The main pipe connects with opposite ends of the box, whereas the branch pipe 34 connects with a side of the box intermediate of its ends. Within the 35 box is arranged a valve 35 pivoted at one end and normally closing the branch pipe 34. A portion of the valve near its free end is deflected, as shown at 36 and is provided with a check valve 37. A deflected or inclined portion 36 extends across the direct path of 40 the current of air between the ends of the main pipe connected to the box 33. The air entering the box a holds the valve 35 seated, but opens the check valve 37 and passes out at b, thence to the four-way coupling E and to the cylinders of the signal means F at each of the other three approaches. When the air comes in the opposite direction, that is, enters the box at b, it 45 opens the valve 35 and passes out through 50 the branch 34, thence into the cylinder 20 and actuates the signal. This latter operation is what takes place at each of the three approaches B, C and D, when a train is moving towards the crossing on the approach A.

A branch pipe 35 connects with the cylinder 29 of the secondary signal G and with the cylinder of the safety appliance H. The main pipe 3 and the branch pipe 35 connect at a point 36' and each is controlled by means of a 60 valve 37 which is connected to the semaphore arm 17 of the primary signal F. When the semaphore arm 17 is lowered, a car or train advances on an approach, as A, and upon reaching an operating air compressor J, forces 65 its charge into the branch pipe 35 so as to

actuate the secondary signal G and the safety appliance H, instead of sending the charge of air to the four-way E and to the primary signals of each of the other three coupling approaches. This is indicated most clearly in 70 Fig. 7. The primary signal F upon the approach A, when set by a train or car upon anyone of the other approaches, moves the valve 37 so as to shut off the air from the pipe 3 at A and opens communication between the 75 pipe 3 and the branch 35 at the valve 37, hence when the engine or train upon the approach A operates the compressor J, the air thus compressed is forced directly to the signal G and the safety appliance H of said approach A.

The safety appliances have an approach embodying a switch 38 and actuating means therefor, the latter embodying two cylinders 39 and 40 and pistons 41 and 42 arranged to 80 operate in the respective cylinders and normally under pressure by means of springs 43 and 44. A branch pipe 35 connects with the upper end of the cylinder 39, and a short pipe 44 connects one end of the cylinder 39 with 85 the adjacent end of the cylinder 40. The stem or rod of the piston 42 connects with the switch bar 45 and when the piston 42 is moved towards the outer end of the cylinder 40, the switch 38 is opened to the main line so as to 90 side track, ditch or otherwise clear the main line of the car or train moving towards the crossing against said signals F and G. A catch 46 engages with a stop 47 of the piston rod to hold the switch when thrown, until the pipe 100 means and operating cylinders are relieved of pressure. A lever 48 fulcrumed to a standard 49 has one end connected with a stem or rod of the piston 49 and its opposite end is provided with a rod or bar 50 which is adapted 105 to engage with a stop 47 and hold the switch out of action so as to permit trains to pass along the main line under normal conditions. The rod or bar 50 besides releasing the switch and its actuating means is also adapted to 110 effect the release of the catch 46 from the stop 47 to permit the switch to move away from the main line after being closed with reference thereto.

When the branch pipe 35 receives air under 115 pressure, the semaphore signal is set to danger and the piston 41 is moved to effect release of the piston 42 and the switch, and the air after operating the piston 41 passes into the cylinder 40 and moves the piston 42 so as to 120 close the switch with reference to the main line to cause the car or train to pass thereover on the siding, branch or spur, thereby avoiding a wreck on the main line and giving the car or train having the right of way a clear 125 track.

The strip 11 is returned to normal position by means of spring 55, the latter normally exerting a pressure to hold the strip 11 against the rail.

- The catch 46 is adapted to be operated by hand to be released from the stop 47, although it may be actuated automatically by means of the piston 41 through suitable connections.
- 5 The semaphore signal illustrated in Fig. 6 is preferred for public roads or street crossings and may be used at any point to indicate danger. It is to be understood that the several cylinders are to be provided with vent 10 openings, so as not to interfere with the free operation of the pistons, thereby providing for ingress and egress of air as the pistons move in and out to transmit movement to the parts connected therewith. It is further 15 noted that roller bearings may be provided between the working parts to reduce friction to a minimum and thereby render the operation more certain and positive with a minimum expenditure of force.
- 20 Having thus described the invention, what is claimed as new is:
1. A signal for railway crossings comprising a compressor for each railway approach to the crossing, signal devices for each approach to the crossing, a pipe line connecting the compressors and signaling devices, means for actuating the compressors from a moving train to charge the pipe lines and operate the signal devices, and a relief for the pipe line 25 adapted to be tripped by the train after passing the crossing and receding therefrom to permit the signal devices to return to normal position.
  2. A signal for railway crossings comprising a compressor for each railway approach to the crossing, signal devices for each approach to the crossing, a pipe line connecting the compressors and signaling devices, means for actuating the compressors from a moving 30 train to charge the pipe lines and operate the signal devices, valves interposed in the pipe lines at the point of connection of the signaling devices therewith to close by the blast of air through the pipe line in one direction, and 35 to open by said blast of air moving in the opposite direction to admit of cutting out certain signals and the actuation of certain other signals according to the direction of approach of the train towards the crossing, 40 and a relief valve for the pipe line adapted to be tripped by the train after passing the crossing and receding therefrom to permit the signaling devices to return to normal position.
  3. In railway signal appliances, the combination of a fluid compressor, a signal device, a pipe line between the signal device and compressor, means for operating said compressor from a moving train, a check 45 valve in the pipe line for preventing back pressure, and a trip between said check valve and the compressor, operating means to effect a bleeding of the pipe lines to permit the parts to return to normal position.
  - 65 4. In railway signal appliances, the combination of a signal device, a compressor, a pipe line connecting the compressor with the signal operating means, a check valve in the length of the pipe line, a compressing spring adapted to actuate the compressor upon the moving of a train in one direction, a trip for said check valve adapted to be operated when the train is moving in the opposite direction.
  5. In signal appliances for railways, the combination of a signal device, a compressor, a pipe line between said compressor and the actuating means of the signal, and a valve in the pipe line having an inclined portion to receive the impact of the current passing through said pipe line, whereby the valve is held closed when the current is in one direction and is opened when the current is in the opposite direction.
  6. In a railway signal, the combination of an air compressor, signal means, a pipe connection between the air compressor and signal means, a depressible strip for actuating the air compressor by the weight of the moving car or train in one direction, said strip having a cut away portion to form a space between an end thereof and the rail, a release valve, and operating means therefor actuated by a rocking or lateral movement of the compressible strip when the train is moving in an opposite direction or receding from the signaling means.
  7. A railway signal, the combination of an air compressor, signal means having pipe connection with the air compressor, a release valve, and a strip mounted to receive both a rocking and a depressible movement, the latter serving to actuate the compressor when the train is moving towards the signal, and the rocking movement serving to actuate the release valve when the train is moving away from the signal apparatus.
  8. In a railway crossing, the combination of a primary and secondary signals for each approach, air compressing means adapted to be actuated by the moving train, pipe connections between the several parts, a valve in the main pipe line for directing the air from the compressor of one approach to the primary signal mechanism of another approach, and a valve adapted to be actuated by the primary signal of one approach to admit of the secondary signal at another approach being operated by the air compressing means of said approach.
  9. In safety appliances for railways, the combination of switches in co-operative relation with the main line, switch actuating means, signal appliances, air compressing means actuated by the moving train, and pipe connections between the air compressing means, signal devices and switch operating appliances, whereby in the event of the signal set against a train going unheeded, said train will be side tracked to permit the

train having right of way continuing its travel with casualty.

10. In safety appliances for railways, the combination of a switch in coöperative relation with a main line, a cylinder and piston for moving said switch, lock devices for holding the switch both opened, and closed, a second cylinder having communication with the first mentioned cylinder, a piston ar-
10 ranged to operate in said cylinder, a lever for releasing the lock devices to permit move-

ment of the switch in each direction, and means for charging said second cylinder to effect release of the switch and primary piston preliminary to moving the switch. 15

In testimony whereof we affix our signatures in presence of two witnesses.
